R. C. D. LEGG.

BOTTLE HOLDER.

APPLICATION FILED JUNE 29, 1908.

926,389.

Patented June 29, 1909.

UNITED STATES PATENT OFFICE.

RODGER C. D. LEGG, OF PATERSON, NEW JERSEY.

BOTTLE-HOLDER.

No. 926,339.

Specification of Letters Patent.

Patented June 29, 1909.

Application filed June 29, 1908. Serial No. 440,865.

To all whom it may concern:

Be it known that I, RODGER C. D. LEGG, a citizen of the United States, residing at Paterson, in the county of Passaic and State of New Jersey, have invented certain new and useful Improvements in Bottle-Holders; and I do declare the following to be a full, clear, and exact description of the invention, such as will enable others skilled in the art to 10 which it appertains to make and use the same.

My invention relates to improvements in bottle holders, designed more particularly for location upon the outside of the house or 15 door or stoop.

It has for its object to provide for the convenient and effective retention of the bottle or jar in place, as against unauthorized removal, and to provide also for the ready 20 removal of the jar or bottle, when it may be desired to remove the contents of the latter, and to carry out these ends in a simple and inexpensive manner.

With these and other objects in view, the 25 invention consists of certain novel features of construction, combination and arrangement of parts, as will be more fully described and particularly pointed out in the appended claims.

30 In the accompanying drawings illustrating the preferred embodiment of my invention, Figure 1 is a perspective view thereof; Fig. 2 is a front view of the upper portion thereof, certain parts being broken away; Fig. 3 is a 35 horizontal section taken on the line 3—3 of Fig. 2; Fig. 4 is a vertical section taken on the line 4—4 of Fig. 2; and Fig. 5 is a detail sectional view of the jar receiving ring taken on line 5—5 of Fig. 2. Fig. 6 is a detailed 40 vertical section taken on the line 6—6 of Fig. 1.

In carrying out my invention, I employ a 45 ring member 1 for receiving the lower end of a jar or bottle, and an upper clasp member 2 for receiving the neck portion of the bottle or jar. The ring member or annulus 1 is pivotally connected as at 3, preferably to one leaf of a hinged or jointed member 4, suitably fastened to the side of a door or 50 stoop of a house. The pivotal connection between the ring member and the hinge or attaching piece, permits said ring to be careened or inclined with relation to the jar or bottle for the ready insertion of the latter 55 thereto. The bottom clasp member 1 is extended and lapped upon itself suitably for

varying it diametrically to conform to the size of the jar or bottle as in receiving the latter. The overlying or lapping portions of the bottom clasp-member have applied thereto and are received by clips or couplings 1^a, adapted to permit of sliding its overlying portions one upon the other, as in accommodating the clasp-member to the jar or bottle and for the retention thereof in position. 60 The free ends of the clasp-member 1 are suitably bent or deflected as at 1^b, 1^c to serve as stops, as against the casual displacement of the couplings or clips 1^a, as will be readily understood. 70

The upper or clasp member 2 consists preferably of a strap of metal formed with a loop 5 for readily receiving the neck of the jar or bottle, said loop having a plate like extension 6 arranged parallel with the corresponding attaching portion 7 of said clasp, connection being suitably effected between said attaching portion, and the stoop or door of a house. Interposed between said attaching portion of the clasp and the stoop 80 or door is a guard or keeper 8, to receive the plate like extension portion of the loop of said clasp. The loop extension portion or plate has attached to it a spring 9 preferably of helical form, suitably fixed in place 85 and adapted to hold said plate like extension under tension or pressure when a bottle neck is inserted within the loop of the clasp. Arranged adjacent to the loop extension or plate 6 are preferably two spring 90 pressed pawls 10 for engagement with the notched or serrated upper edge 11 of said plate or extension to retain the latter with the loop in effective position when adjusted to the bottle-neck, as against the removal of 95 the bottle or jar therefrom. A suitable casing or inclosure 12 fastened to the stoop or door, over the pawl engaged portion of the slide or extension of the clasp loop, prevents unauthorized access being had to said pawl 100 engaged parts when in locked position.

It will be noted that by suitably tilting the ring member 1, as above indicated, a jar or bottle may be received thereto at its lower or bottom end, when by bringing the bottle into a perpendicular position said ring will be caused to assume its initial position, and with the clasp or loop in unlocked position, the neck of the bottle may be inserted into said loop, and then by compressing said 110 loop, as in sliding its extension or plate portion toward the bottle, said clasp or loop is

caused to closely encompass the neck of the bottle, and thus be held by the automatic engagement of the pawls 10 with serrated or notched surface of the extension or plate 5 of said loop, thus providing for locking the bottle in effective position as against surreptitious removal.

By the insertion of a suitable implement, through an opening or openings 13 for engaging the pawl or pawls in engagement with the loop sliding extension, the clasp, under the action of its spring will be automatically released from the neck of the bottle, and by suitably manipulating the bottle, 10 it may be readily removed from said clasp and the bottom engaging ring, as required.

It will be noted that by reason of the foregoing arrangement of parts, a simple, inexpensive and effective device of the character 20 described is provided for its intended purpose, whereby the bottle or jar may be readily inserted in place, and securely held therein and quickly removed.

From the foregoing description, taken in 25 connection with the accompanying drawings, the construction and operation of the invention will be readily understood without requiring a more extended explanation.

Various changes in the form, proportion 30 and the minor details of construction may be resorted to without departing from the principle or sacrificing any of the advantages of this invention as defined in the appended claims.

35 Having thus described as ascertained the nature of my invention, what I claim as new and desire to secure by Letters-Patent, is:—

1. A device of the character described 40 comprising a ring member, and a clasp member, said ring member having pivotal connection with its attaching means, and means for securing said clasp member in locked position.

45 2. A device of the character described

embracing a ring member, a hinge member, said ring member having pivotal connection with said hinge member, a clasp member having a loop forming portion provided with a slide or extension, and means for engaging and retaining said slide or extension in locked position. 50

3. A device of the character described comprising a ring member, a clasp member arranged directly above said ring member, 55 and having a plate like extension provided with a notched or serrated upper edge, and a spring pressed pawl for engagement with said notched or serrated edge.

4. A device of the character described embracing a ring member, a clasp member arranged in alinement with said ring member, a keeper or guard, said clasp member having a slide or extension formed with a serrated or notched edge received by said keeper or 60 guard and a spring pressed pawl or detent adapted to engage the serrated or notched edge of said extension, and an inclosure for said pawl and the pawl engaged portion of said slide or extension. 70

5. A device of the character described embracing a pivot ring member adapted to receive the lower end or bottom of a bottle, a clasp member having a loop forming portion adapted to receive or encompass the neck 75 portion of said bottle, and having its loop forming portion provided with a slide or extension having a notched or serrated edge, a resilient member for the retention of said slide under stress or tension, and a spring 80 pressed pawl for engaging the notched or serrated edge of said slide.

In testimony whereof I have hereunto set my hand in presence of two subscribing witnesses.

RODGER C. D. LEGG.
